UNITED STATES PATENT OFFICE.

FREDERICK K. VREELAND, OF MONTCLAIR, NEW JERSEY.

ELECTRICAL OSCILLATOR.

Application filed May 3, 1920. Serial No. 378,435.

To all whom it may concern:

Be it known that I, FREDERICK K. VREELAND, a citizen of the United States, residing at Montclair, in the county of Essex and State of New Jersey, (post-office address No. 55 Liberty Street, New York city), have invented certain new and useful Improvements in Electrical Oscillators, of which the following is a specification.

10 The invention herein described relates to an improvement in electric oscillators, particularly oscillators of the regenerative type, in which energy is supplied from a source of power to an oscillating circuit in 15 synchronism with the oscillations, and the energy supply is controlled by the oscillations themselves.

In my U. S. Patents No. 829,447, No. 829,934 and No. 973,826, I have described 20 various forms of oscillators of this type, in which the supply of energy to the oscillating circuit is introduced through a sensitive gap or gaps, and controlled by a magnetic or electrostatic field produced or 25 controlled by the oscillations in the oscillating circuit. In my U. S. Patent No. 1,340,193, dated May 18, 1920, I have described an improvement in oscillators of this type, whereby purity of wave form is 30 secured, and including the feature of an oscillating circuit having inductance and capacity reactances which are large with respect to the other impedances of the system with which it is associated. The specific means there set forth for securing this 35 result includes a step-down coupling of the system including the power circuit to the oscillating circuit. This latter specific feature is peculiarly applicable in the case where the sensitive gap employed is a thermionic tube having high impedance, as is 40 fully explained in that application.

The present invention relates to another application of the principle of securing approximately pure sinusoidal oscillations by 45 means of a heavily loaded oscillating circuit, flexibly coupled to the power system; that is, an oscillating circuit having inductance and capacity reactances which are 50 large with respect to the effective impedance of the system with which it is associated, and in the present case coupled thereto by a step-up transformer or by an equivalent electrostatic or other coupling, 55 and particularly applicable in an oscillator including a sensitive gap having relatively

low impedance, such as the mercury arc oscillators described in my patents above cited. It involves other novel and useful features herein set forth.

60 In the drawing, Fig. 1 shows an application of the invention to a mercury arc oscillator controlled by a magnetic field.

Fig. 2 shows an application to an oscillator of the negative resistance type, such as 65 is described in my U. S. Patent No. 1,52,675.

In certain forms of electrical oscillator the wave form of the oscillation is very impure because of the non-sinusoidal character of the power supply and the rigid coupling of the oscillating circuit to the sensitive gap or other power transforming medium. By the use of the present invention I obtain a result analogous to that 70 secured by a heavy fly wheel connected to its prime mover by a flexible or yielding coupling, the large momentum of the fly wheel and the flexibility of the coupling co-operating to absorb irregular fluctuations 75 in the driving force.

I employ a heavily loaded oscillating circuit, flexibly coupled to the power system; that is, an oscillating circuit whose capacity and inductance reactances are large with respect to the impedance of the coupling means and its associated circuits, relative 80 to the oscillating circuit, adapting the secondary of the coupling means to the requirements of relatively free oscillation, and adapting the primary to the requirements 85 of absorbing and transmitting energy from the energy transforming medium to the oscillating circuit. The coupling is designed to secure an efficient energy transfer without imposing rigidity on the oscillating circuit.

The present invention is adapted particularly to use in connection with a sensitive gap or other power transforming medium 100 of relatively low impedance. With such a medium it is desirable to employ a step-up coupling between the power circuit and the oscillating circuit, so that the conditions above stated may be met with an oscillating system having elements of convenient proportions. The secondary impedance is 105 made small with relation to the other impedances of the oscillating circuit, the secondary of the coupling means thus being adapted to sustain the oscillations without forcing irregularities upon them, and the 110

primary being adapted to absorb and transmit energy freely from the power transmitting medium, which is one of small impedance carrying relatively large currents at 5 a low voltage, such as a high vacuum mercury vapor tube, or a medium of intermediate characteristics, such as various forms of electric arc. The coupling may be electromagnetic, as in the four examples here 10 illustrated, or electrostatic, as in Fig. 2 of my Patent No. 1,340,193 above referred to.

Considering specifically the case of an electromagnetic coupling, which I prefer, the power circuit is associated with the oscillating circuit by a transformer whose secondary, located in the oscillating circuit, has an impedance sufficiently small with respect to the inductance and capacity reactances of the oscillating circuit to prevent undue distortion of the wave form, and whose primary is so related to the electrical constants of the sensitive gap or other energy transforming medium as to insure an efficient transfer of energy. In general, the primary 20 reactance should be comparable to the impedance of the power transforming medium. Usually I prefer to employ a close coupling between the primary and the secondary, or specifically one in which the major part of 25 the inductance of the power circuit is inter-linked with the secondary. This close coupling, however, does not impose rigidity on the oscillating circuit, since the secondary reactance is small compared to the other 30 reactances of the circuit.

The ratio of transformation is a step-up ratio and the condition of securing sinusoidal oscillations is complied with by making the inductance reactances of the coils L, L' and the capacity reactance of the condenser C large with respect to the other impedances of the oscillating system. Thus the impedance of the secondary s is made small with respect to these reactances, and the ratio of this impedance to the primary 40 impedances of p_1 and p_2 is designed to suit the impedance of the sensitive gap. It will be understood that, when comparing the impedances of the oscillating system, the primary impedances will be reduced to their 45 equivalent impedances in the oscillating circuit, as determined by the ratio of transformation of the coupling transformer.

When the power transforming medium is 50 a sensitive gap of low impedance, such as the various forms of mercury or other arcs, described in my patents referred to Nos. 829,447, 829,934, and 973,826, the current drawn from the power supply is usually 55 comparatively large, and the primary fluctuations or oscillations of this current produced by the control field are also relatively 60 large.

In the preferred form of apparatus shown 65 in these patents, the oscillating circuit is di-

rectly connected to the sensitive gap or gaps, so that the oscillations in this circuit have the same order of magnitude as the fluctuations of the power current. It is not always convenient, however, to use currents in 70 the oscillating circuit of the same order of magnitude as the power currents. In the case of my patent 1,340,193 herein referred to, the fluctuations of current in the thermionic bulb are relatively very small, hence a 75 step-down coupling is provided which permits the use of relatively large currents in the oscillating circuit. On the other hand, it is sometimes desirable to employ an oscillating circuit carrying currents much 80 smaller than the current fluctuations of the power circuit. In such cases a step-up coupling is desirable. Such a case arises, for example, in a mercury arc oscillator when very low frequencies are to be generated. 85 To secure such low frequency without the use of excessively large condensers requires a large inductance in the oscillating circuit. When the inductance is too large to be effectively connected directly to the power 90 circuit, I make use of the step-up coupling illustrated in Fig. 1. Here, the power current supplied to the sensitive gap traverses two primary coils, p_1 , p_2 , connected respectively to the anodes A₁, A₂, both being coupled inductively to a secondary coil s, in the 95 oscillating circuit, including capacity C and inductance L L'. These inductances in the form of apparatus shown in this figure are employed as field coils to perform the magnetic control or commutation of energy in the sensitive gap.

Fig. 2 shows an application of the invention to an oscillator of the negative resistance type, such as described in my U. S. Patent No. 1,152,675. A similar arrangement is effective in connection with an arc oscillator of the well known type. It is particularly useful in connection with the arc oscillator because of the wide departure 105 of the power current from the sinusoidal form due to the extinction of the arc at each oscillation.

In this arrangement, as in the other, the power circuit includes a primary coil p_1 of 110 impedance comparable to the impedance of the arc or generator tube, coupled, preferably closely, to a secondary coil s_1 in the oscillating circuit, s_1 , L, C L', the secondary 115 impedance being small with respect to the inductance and capacity reactances. By virtue of this coupling and proportioning of the system oscillations of approximately 120 pure wave form are secured notwithstanding the irregular character of the power supply. 125

I claim—

1. In an electrical oscillator, a power transforming medium, a power circuit associated therewith, a heavily loaded oscillat- 130

ing system, and a step-up coupling means between the circuits which is flexible with relation to the oscillating circuit and stiff with relation to the power circuit, substantially as set forth.

2. In an electrical oscillator, a power transforming medium, a power circuit associated therewith and step-up coupling means between the oscillating circuit and the power circuit whose mutual reactance constitutes a small part of the capacity and inductive reactance of the oscillating circuit and a relatively large part of the reactance of the power circuit, substantially as set forth.

15 3. In an electrical oscillator, a power transforming medium of low impedance, a power circuit associated therewith, an oscillating circuit associated with the power circuit by a transformer having a primary reactance comparable with the impedance of the energy transforming medium and a larger secondary reactance that is small compared to the capacity and inductance reactances of the oscillating circuit, substantially as set forth.

25 4. In an electrical oscillator, a power transforming medium of low impedance, a power circuit associated therewith, an oscillating circuit associated with the power circuit by a transformer having a primary reactance comparable with the impedance of the energy transforming medium and a larger secondary reactance that is small compared to the capacity and inductance reactances of the oscillating circuit, and a close coupling between the primary and secondary reactances, substantially as set forth.

30 5. In an electrical oscillator, a power transforming medium, a power circuit associated therewith, and an oscillating circuit associated with the power circuit by a

step-up transformer whose primary reactance is comparable to the impedance of the power transforming medium and whose secondary reactance is small with respect to 45 the reactances of the oscillating circuit, substantially as set forth.

6. In an electrical oscillator, a power transforming medium of low impedance, a power circuit associated therewith, an oscillating circuit associated with the power circuit and step-up coupling means between the power circuit and the oscillating circuit comprising the major part of the reactance of the power circuit and a minor part of the 50 reactance of the oscillating circuit, substantially as set forth.

7. In an electrical oscillator, a power transforming medium of low impedance, a power circuit associated therewith and an 60 oscillating circuit associated with the power circuit by a step-up coupling whose secondary reactance is small compared with the reactances of the oscillating circuit, substantially as set forth.

8. In an electrical oscillator, a power transforming medium of low impedance, a power circuit associated therewith, an oscillating circuit associated with the power circuit by a step-up coupling whose reaction on the oscillating circuit is small compared with the other reactances of the circuit, and means whereby the oscillations of the oscillating circuit control the transfer of energy in the power transforming medium, 75 substantially as set forth.

This specification signed and witnessed this 30th day of April, 1920.

FREDERICK K. VREELAND.
